LAMP

Filed April 4, 1928

UNITED STATES PATENT OFFICE.

CHARLES MAINS AND FREDERICK BATTEIGER, OF COLUMBUS, OHIO.

LAMP.

Application filed April 4, 1928. Serial No. 267,155.

This invention relates to an improved lamp base, and has for its primary object the provision of a lamp base which, when not in use, may be folded or collapsed into extremely compact form to permit the base to be readily carried from place to place and in a convenient and space saving manner.

It is an outstanding object of the present invention to provide a collapsible or foldable lamp standard or base adapted especially for the convenience of the travelling public, for the purpose of enabling the latter to be provided with an efficient, light weight portable lamp which may be used effectively when actively positioned for any desired purpose, but which when not in use may be stored away in a traveling bag or other luggage carrier without requiring any considerable room therein.

In accordance with the present invention a lamp base or standard is provided which possesses approximately the diameter of an ordinary incandescent lamp socket. The base is of tubular construction and is adapted to receive a plurality of foldable leg members, which when the lamp is in operation, assume extended or projected positions to comprise a base enlargement by means of which stability is imparted to the lamp when the latter is set up for use, the relationship, however, between the legs and the tubular standard being such that when the lamp is not in use the legs are folded into the tubular standard and are disposed within the confines of the latter for the purpose of providing economy in storage space.

With these and other objects in view, which will appear as the description proceeds, the invention accordingly consists in the novel features of construction, combinations of elements and arrangements of parts, hereinafter fully described and pointed out in the appended claims.

45 In the accompanying drawings:

Figure 1 is a view partly in side elevation and partly in vertical section of a lamp standard constructed in accordance with the present invention, the legs of the standard being shown in their extended positions,

50 Figure 2 is a similar view disclosing the legs of the standard in their collapsed or withdrawn position,

Figure 3 is a horizontal sectional view on the line 3—3 of Figure 1,

55 Figure 4 is a horizontal sectional view on the line 4—4 of Figure 1, and

Figure 5 is a vertical sectional view through the lower portion of the lamp base.

Referring more particularly to the drawings the numeral 1 designates the lamp base or standard comprising the present invention. The base comprises a tubular standard 2, preferably formed from thin sheet brass and which has its exterior surfaces 65 suitably lacquered or otherwise ornamented to present an attractive appearance. The standard 2 is of substantially uniform diameter throughout the length thereof, and it will be observed that the diameter of the 70 standard conforms approximately to that of an ordinary bulb socket or base 3, which is carried by the upper part of the standard 2. It will be appreciated that the socket 3 is of conventional form, and may be 75 provided with the usual switch plunger 4 for the purpose of controlling the passage of current to an associated incandescent lamp adapted to be carried as usual in the socket 3, although when the lamp is being 80 taken from place to place the incandescent bulb ordinarily is not carried as an integral part of the lamp.

Connected with the lower part of the socket 3 is a boss 5, which is internally 85 threaded for the reception of the upper end of a conduit 6. The lower end of this conduit is received within a disk 7 which serves to close the lower end of the standard 2. The disk 7 is secured rigidly to the standard 90 by means of screws or their equivalents 8.

A current conveying cable 9 is adapted to pass through the conduit 6, and the upper end of the cable 9 is connected with the socket 3 in the usual manner, the outer end 95 of the cable is also connected with a plug 10 of conventional form which is adapted to be inserted in a lamp socket, not shown. The cable 9 is of any suitable length and is adapted to be wrapped around the exterior 100 of the standard 2 when the lamp is not in use.

Arranged within the standard 2 and slidably mounted upon the conduit 6 is a spool 11. The lower head 12 of this spool has 105 its peripheral portion provided with spaced

notches 13, and between these notches there is formed a projection 14. The projections 14 are adapted to be positioned within bearing openings 15 provided in the upper end 5 of a plurality of curved leg sections 16 which leg sections, as shown in Figure 2, are adapted to be positioned within the standard 2 when the lamp is not in active use. The leg sections are gradually curved and 10 have their outer ends circularly bent as at 17 to provide a supporting base for the lamp. The leg sections pass through slots 18 formed in the perimeter of the disk 7, the slots in turn being provided with beveled 15 faces 19, which are employed to direct the leg sections outwardly and laterally when the latter are being withdrawn from the standards.

Slidably mounted upon the spool 11 is a 20 pressure washer 20. This washer is normally pressed into engagement with the inner end of the leg section by means of a relatively strong spring 21, which is arranged helically between the washer 20 and the upper head of the spool 11. It will be seen 25 that the action of the spring 21 is to force the washer 20 downwardly. This imparts frictional pressure to the leg sections which serves to positively maintain the latter in either their collapsed or extended positions. 30 For example, as shown in Figure 1, the washer 20 is forcing downwardly on the laterally bent ends of the leg sections with sufficient pressure so that the leg sections 35 fulcrum about the projections 14 and come into frictional contact with the beveled walls 19 and the lower edges of the standard 2. By this arrangement the leg sections are positively maintained in their extended or 40 spread positions, providing an enlarged base area for the lamp so that when the latter is deposited on a table or other form of support it will possess all necessary stability present in the customary table type of lamp. 45 When the leg sections are collapsed or folded, as shown in Figure 2, the spring 21 presses upon the upper ends of said leg sections with sufficient pressure to positively maintain said leg sections in such collapsed or folded positions. If desired, the conduit 50 6 may be surrounded by means of a weak spring 22 of considerably less strength than the major spring 21. The spring 22 also assists in maintaining the leg sections in their 55 collapsed positions but does not interfere with the opening or extending of said leg sections to assume the position disclosed in Figure 1.

In view of the foregoing it will be seen 60 that the present invention provides a lamp standard or base which when not in use will occupy but a minimum of space and may be conveniently stored and carried in an ordinary travelling bag. The construction of 65 the lamp standard is such as to present no

sharp projections or jointed parts so that there will be nothing about the lamp to tear or catch into fabrics or garments which may be also carried in the same travelling bag as the lamp. To place the lamp base in use 70 it is merely necessary to draw outwardly on the leg sections, which can be very easily accomplished and by the provision of the spring arrangement described such leg sections will be locked automatically in their 75 extended positions. While we have described what we consider to be the preferred form of the present invention, nevertheless it will be understood that variations in construction and arrangement from that herein specifically described may be made without departing from the scope and spirit of the invention, as the latter has been expressed in the following claims.

What is claimed is:

1. A lamp base comprising a standard of hollow tubular form, a bulb socket carried by the upper end of said standard, a closure having peripheral slots positioned in the opposite ends of said standard, a conduit 85 extending between said closure and said bulb socket, a spool slidably mounted upon said conduit, and a plurality of pivotally movable legs carried by said spool, said legs being arranged to project through the slot 90 in said closure.

2. A lamp base comprising a hollow tubular standard, a socket member positioned in the upper end of said standard, a disk located in the lower end of said standard, said disk being provided adjacent to its periphery with spaced slots, a conduit arranged axially within said standard and uniting said socket member with said disk, a spool slidably mounted upon said conduit and arranged within said standard, and a plurality of foldable leg sections carried by said spool and movable in unison therewith, said leg sections being adapted to project through the slots in said disks.

3. A lamp base comprising a hollow standard, a socket member adapted for the reception of an incandescent bulb secured to the upper end of said standard, said standard conforming substantially to the 100 diameter of said socket member, a support slidably mounted within said standard, and a plurality of foldable leg sections carried by said support, said leg sections being adapted to be received within said standard 105 when inactively positioned and to project beyond said standard when actively positioned, and means for yieldingly holding said leg sections in active to inactive positions.

4. A lamp base comprising a hollow standard, a bulb socket carried by the upper end of said standard, a peripherally slotted disk fixed in the lower ends of said standard, a conduit uniting said disk and said 110

socket, said conduits being disposed axially within said standard, a plurality of leg sections extending through the slots in said disks, a spool slidably mounted on said conduit and having pivotal connections with said leg sections, and spring means acting on said leg sections and carried by said

spool to maintain the leg sections positively in active or inactive positions.

In testimony whereof we affix our signatures.

CHARLES MAINS.
FREDERICK BATTEIGER.
